BY C. P. Goepel
ATTORNEY.

UNITED STATES PATENT OFFICE.

ABRAHAM C. FISHER, OF NEW YORK, N. Y.

BAG.

Application filed May 11, 1922. Serial No. 560,035.

To all whom it may concern:

Be it known that I, ABRAHAM C. FISHER, a citizen of the United States, and a resident of the borough of Manhattan, in the city, county, and State of New York, have invented certain new and useful Improvements in Bags, of which the following is a specification.

This invention relates to hand bags, and more particularly has for its object to provide a convenient bag for ladies, namely, a combination of bag and vanity case, so that the user may have within convenient reach both the usual contents of a lady's hand bag and the usual accessories attending vanity cases.

The object of the invention is to provide a very complete combination bag and vanity case which may be readily used for either purpose, and the invention will be more fully understood with the aid of the following drawings and finally pointed out in the accompanying claims.

In the accompanying drawings:

Fig. 1 is a front view of my improved combination bag and vanity case;

Fig. 2 is a side view thereof;

Fig. 3 is a rear view;

Fig. 4 is a front view with the bag portion entirely open so that access may be had to the contents of the bag;

Fig. 5 is a sectional view of Fig. 4 on line 5—5 of Fig. 4, showing also how the cover of the bag is separated from the cover of the vanity case;

Fig. 6 is a front view showing the bag closed but the vanity case open;

Fig. 7 is a sectional view of Fig. 6 taken on line 7—7 of Fig. 6;

Fig. 8 is an enlarged view of the hinge, and

Fig. 9 is a partial section on line 9—9 of Fig. 2.

Similar characters of reference indicate corresponding parts throughout the various views.

Referring to Fig. 1, the body of the bag is formed with a base 10 supported by buttons 11 or the like, and the shape of the body tapers upwardly so that the upper portion, indicated by 12, is smaller than the base portion. To the sides of the body are attached eyelet supports 13, one on either side of the bag, and to these eyelets 13 are secured

the ends of a handle in the form of a chain-like braid, indicated by 14. The handle is broken off in the drawings and may be of any suitable size, and is of the usual loop-shape. In the same manner that the base portion 10 is larger than the upper portion 12, as shown in the front view in Fig. 1, the side view also has the base portion 10 larger than the upper portion 12 so that the sides taper upwardly, and similarly the rear sides of Fig. 3. To the upper portion of the body of the bag there is hinged at 15, the metal frame 20 of an inner lid. The frame extends around the upper portion 12 of the bag, and has at the front thereof an engaging member 16 which has a flat shape with cut-outs 17 at either side thereof, best shown in Fig. 4. The frame itself has a section shaped in the form of the letter T, so that a part of the frame extends outwardly over the top edge of the body of the bag and hugs the upper edge thereof. To the frame 20 is secured a lid 21 made of suitable material as silk or the like, which is preferably continuous with the lining of the interior of the body of the bag. This lid forms an inner cover to the bag when the frame 20 is in its downward position and has its member 16 engaged by the fastening device 18 secured to the bag proper. To one side of the inner lid is secured by sewing or the like, a pocket 22 which has its lower portion secured to the lid 21, as also the side portions, and has its upper portion, indicated by 23, open so as to form a pocket on one side of said lid. Within this pocket a writing pad 24 with pencil 25 may be removably inserted. Within the body of the bag another pocket 26, shown at dotted lines in Fig. 4, is arranged, within which a small-change pocket-book 27 may be removably placed.

On the outer surface of the lid is arranged another pocket, indicated in Fig. 5 by the character 28, with its open end extending upwardly, and this pocket is usually used for powder puffs and the like, so that it may be put into use when the outer top or cover 30 which is hinged at 15 to the bag proper is open. The outer top cover 30 is provided with a fastening device in the form of a ball, indicated by 31, which engages the other recess 17 of the engaging member 16. When the top cover 30 has its fastening de-

vice 31 inserted within the recess 17 of the member 16, the edge of the upper margin of the body of the bag snugly fits within the upwardly extending leg of the T-shaped frame 20 of the inner lid, so that when the bag is entirely closed by the engagement of its fastening device, the outer cover snugly fits within the frame of the body of the bag and a very pleasing effect is given to the combination bag and vanity case by virtue of this coaction of the parts. This is clearly seen in Fig. 1. The inner part of the cover 30 is provided with a mirror 29, as shown in Figs. 6 and 7, which being supported on 15 the cover 30 which in turn is hinged at 15, may be used when the vanity case is utilized.

It will be noted that the frame 20 is hinged. The frame 20 has a double hinge projection 45 and 46 (see Fig. 4), provided 20 with openings into which the pivot pin seats. Intermediate these projections is the projection 47 of the frame 20 also provided with an opening into which the same pivot pin seats. Upwardly from the body of the bag extends the hinge projection 48 also provided with an opening through which the pivot pin passes. The pivot pin is hidden within the frame 20 and within the cover which passes over the same, as shown in 25 Fig. 4. Covering of the body of the bag at the rear is preferably continuous and uninterrupted, as shown in Figs. 5 and 7, and also in Fig. 3. The frame 20 may be suitably engraved to enhance the general appearance of the same.

It will be seen from Fig. 9 that the frame 20 consists of the vertical member and the two inwardly projecting members 40 and 41, into which is fitted the lid, and 40 this frame extends all around the sides and the front portion of the bag, and is hinged at 15 as heretofore described. From Fig. 6, it will be seen how the inner lid and outer cover of the bag fit into the frame 45 20. The cardboard or other stiffening member 34 is enclosed by the covering 35. At the interior is the interior lining 43. In Fig. 9, the cardboard is bent around the edges, as shown, and covered by the leather 50 covering, and these hold the fabric to which the mirror 29 is secured.

The combination bag and vanity case is preferably made of cardboard or other stiff material and covered with a flexible and 55 attractive fine leather covering.

My invention has particular application to the present uses and styles, and forms a very convenient device in that as the user desires, either the vanity case proper may 60 be utilized by the mere opening of the snap device, or, the bag proper may be utilized by a similar simple movement, and in either case the action of the one is independent of the other. That is, when the bag is not desired to be used the vanity case may be used,

and when the vanity case is not desired to be used, the bag may be used. But although these parts are independent in their uses, they are so co-related and combined that by virtue of the bag proper and the top proper fitting snugly within the intermediate frame, a co-operation of parts of a novel nature is produced.

I have described an embodiment of my invention, but changes may be made there- 75 in without departing from the spirit there- of, and these I reserve the right to make and use within the scope of the appended claims.

I claim:

1. A combination bag and vanity case, comprising a body having a base portion larger than the upper portion, a frame T-shaped in cross section hinged to the upper part of said body, an outer cover hinged to the body at the same point as said frame, a lid supported by said frame and provided on its inner side with means for holding devices suitable for general uses, and means on the other side of said lid for holding the devices suitable for use as a vanity case, the outer cover being operable independently of the inner lid, both the upper part of the body of the bag and the margin and the outer cover being held within said frame when the outer cover is closed. 80 90 95

2. A combination bag and vanity case comprising a body having a base portion and an upper portion consisting of upwardly extending substantially flat side and end 100 walls, a hinge along the upper portion of one of the side walls of the body, an outer substantially flat cover having depending edge portions connected to said hinge, a partition intermediate the bag proper or 105 body and the outer cover being fixedly connected with said body and cover only by means of a connection with said hinge on the upper portion of the side wall, and a frame extending around the edge of the 110 partition into which frame the upper portion of the bag and outer cover snugly fit when the partition and cover are closed downwardly upon the bag.

3. A combination bag and vanity case, comprising a body having a base portion and an upper portion consisting of upwardly extending substantially flat side and end walls, a hinge along the upper portion of one of the side walls of the body, an 115 outer substantially flat cover having depending edge portions connected to said hinge, a partition intermediate the bag proper or body and the outer cover being 120 fixedly connected with said body and cover only by means of a connection with said hinge on the upper portion of said side wall, a projecting member on the free front margin of said partition, a fastening member 125 on the front upper margin of said body 130

adapted to engage with one side of said projecting member, a fastening member on the free front margin of the cover adapted to engage the other side of the projecting member, and a frame extending around the edge of the partition into which frame the upper portion of the bag and outer cover

snugly fit when the partition and cover are closed downwardly upon the bag.

In testimony that I claim the foregoing as my invention, I have signed my name hereunder.

ABRAHAM C. FISHER.
